3 Claims. (Cl. 208—310)

This invention relates to separation processes using molecular sieves and particularly to processes for the separation of straight-chain hydrocarbons from petroleum fractions.

It is well known that certain natural and synthetic zeolites have the property of preferentially absorbing certain types of hydrocarbons. These zeolites, known as molecular sieves, have crystalline structures containing a large number of pores of uniform size. In different zeolites, these pores may vary from 4 Å. to 15 Å. or more in diameter, but in any one zeolite the pores will be of substantially uniform size.

It has previously been proposed to treat petroleum fractions ranging from gasoline to gas-oils and higher with molecular sieves having pore diameters ranging from 4 Å. to 15 Å. In order to separate straight-chain hydrocarbons from branched-chain and/or cyclic hydrocarbons a molecular sieve having pore diameters of 5 Å. is suitable. Such a process may be used to recover a denormalised fraction, for example gasoline of higher octane number due to the removal of low octane normal paraffins. The absorbed straight-chain material may also be recovered as a product if desired. For example, a process suitable for separating normal paraffins from petroleum fractions boiling within the C₁₀—C₂₀ range is described in our co-pending application No. 3,965/61.

According to the present invention a process for separating straight-chain hydrocarbons from petroleum fractions boiling above C₁₀ and containing molecular sieve deactivating hydrocarbons comprises fractionating the feedstock to obtain a lower-boiling fraction substantially free of deactivating hydrocarbons and a higher-boiling fraction containing substantially all the deactivating hydrocarbons and treating each fraction with a 5 Å. molecular sieve in separate systems to extract straight-chain hydrocarbons.

It has been observed that, under equilibrium conditions, the affinity of n-paraffin for molecular sieves increases with increasing molecular weight. Petroleum fractions generally contain small quantities of hydrocarbons which boil outside the nominal boiling range of the fraction, for example up to 0.1% of C₂₅ hydrocarbons may be present in a nominal C₁₀—C₂₀ range gas oil. It is believed that the deactivation rate is at least partially due to the accumulation of high molecular weight hydrocarbons in the sieve pores, these high-boiling hydrocarbons being less readily displaced during the normal desorption stage. In the present application, molecular sieve deactivating hydrocarbons means these high-boiling straight-chain hydrocarbons which may, for example, be C₁₈ hydrocarbons or higher.

It is desirable to ensure that substantially all the high-boiling deactivating hydrocarbons are obtained in the higher-boiling fraction but at the same time to ensure that as much as possible of the lower-boiling, non-deactivating material is obtained in the lower-boiling fraction. Preferably, therefore, the feedstock is fractionated at a point within the range 220 to 300° C., and particularly just below the initial boiling point of n-C₁₈ hydrocarbons, i.e. in the region of 300° C.

By fractionating the feedstock and treating each of the fractions in separate molecular sieve systems according to the present invention, deactivation is substantially limited to the sieve used to treat the higher-boiling fraction. The quantity of sieve required to treat the higher-boiling fraction is much less than that which would be required to treat the unfractionated feedstock; also it has been observed that the deactivation rate is substantially independent of the amount of lower-boiling hydrocarbons present in the feed to the sieve, so that the deactivation rate is the same when treating the higher-boiling fraction as when treating the unfractionated distillate. There is, therefore, a saving during regeneration since, although the sieve used for treating the higher-boiling feedstock has to be regenerated after a similar on-stream period as a sieve used for treating unfractionated distillate, the quantity of sieve involved is much less. Regeneration may be carried out in the conventional manner by contacting the deactivated sieve with an oxygen-containing gas under controlled conditions to burn off the deactivating material. A further advantage of operating according to the present invention is the increase in yield obtained. This is due partly to the fact that the sieve used for treating the lower-boiling fraction is not deactivated to any great extent and, in addition, to the fact that the sieve has a higher initial capacity when treating the lower-boiling fraction than when treating either the heavier fraction or the unfractionated distillate. Yet another advantage is that optimum conditions may be chosen in each molecular sieve system to suit the boiling range of each fraction whereas in a process for treating a wide boiling range feedstock in a single molecular sieve system, it is difficult to choose conditions which are suitable both for treating the higher boiling materials and the lower boiling materials present in the feedstock.

The method of the present invention may be employed to treat any hydrocarbon feedstocks which contain deactivating hydrocarbons and any appropriate molecular sieve treatments may be used to treat the fractions separated. A particularly suitable molecular sieve treatment for hydrocarbon feedstocks boiling in C₁₀—C₂₀ range is described in our co-pending U.K. application No. 3,965/61. This process is isothermal and comprises contacting the fraction with a 5 Å. molecular sieve in a first stage to absorb straight-chain hydrocarbons, contacting the sieve with a purging medium in a second stage to remove material absorbed on the surface of the sieve or held interstitially between sieve particles, desorbing the absorbed hydrocarbons in a third stage using either n-pentane or n-butane as desorbing medium, all three stages being in the vapour phase, the pressure in the desorption stage being equal to, or greater than, the pressure in the absorption stage, and recovering the desorbed straight-chain hydrocarbons in a purity of at least 95% weight. Preferred process conditions include a temperature within the range 300—450° C., preferably 350—390° C., and a pressure within the range 0—300 p.s.i.g. preferably 100—150 p.s.i.g. In the present invention, preferred conditions for treating the lower boiling fraction are 380° C. and 150 p.s.i.g. and for treating the higher boiling fraction 380° C. and 125 p.s.i.g.

The invention is illustrated by means of the following comparative example:

Example

A 180—340° C. petroleum distillate was fractionated to give a fraction boiling below a nominal temperature of 243° C., this fraction containing 0.01% weight of sulphur, and a fraction boiling above a nominal 243° C., this fraction containing 0.025% weight of sulphur. Each fraction was treated for the recovery of normal paraffins with 1300 g. of 5 Å. molecular sieve in separate three-

stage cyclic systems under the conditions set out in the following table:

Thus an increase in n-paraffin yield of 6630 grams was obtained by operating according to the present invention.

Stage	Agent	Lower boiling fraction				Higher boiling fraction			
		Temperature, °C.	Pressure, p.s.i.g.	Space Velocity	Period, mins.	Temperature, °C.	Pressure, p.s.i.g.	Space Velocity	Period, mins.
Absorption	{Feed Nitrogen}	350	150	{ 0.6 LHSV 120 GHSV }	6	380	125	{ 0.6 LHSV 120 GHSV }	6
Purge	Nitrogen	350	150	120 GHSV	6	380	125	120 GHSV	6
Desorption	n-Pentane	350	150	1.0 LHSV	12	380	125	1.2 LHSV	12

For purposes of comparison a sample of the original unfractionated distillate was treated with 2600 grams of 5 A. molecular sieve under the conditions indicated above for the higher boiling fraction.

The variation of sieve capacity in each of the three systems with time is indicated in the accompanying graph.

It is seen from the graph that substantially no sieve deactivation took place during the treatment of the lower-boiling fraction over a period of 300 hours. During the treatment of the higher-boiling fraction the sieve was deactivated progressively and, moreover, the initial capacity of the sieve was lower than when treating the lower-boiling fraction. During the treatment of the unfractionated distillate, the initial capacity and the decay rate of the sieve were observed to be the same as during the treatment of the higher-boiling fraction.

The yields of n-paraffins obtained from the three systems were as follows:

	Grams
Lower boiling fraction	19,890
Higher boiling fraction	13,260
Total	33,150
Original distillate	26,520

We claim:

1. A process for separating straight-chain hydrocarbons from petroleum fractions boiling above C_{10} and containing molecular sieve deactivating hydrocarbons comprising fractionating the feedstock at a temperature within the range of 220-300° C. to obtain a lower-boiling fraction substantially free of deactivating hydrocarbons and a higher-boiling fraction containing substantially all the deactivating hydrocarbons and treating each fraction with a 5 A. molecular sieve in separate systems to extract straight-chain hydrocarbons.
2. A process as claimed in claim 1 for the treatment of feedstocks comprising petroleum fractions boiling within the C_{10} - C_{20} range.
3. A process as claimed in claim 1 wherein the feedstock is fractionated at a temperature of the order of 300° C.
